UNITED STATES PATENT OFFICE.

WILLIS S. SHERMAN, OF MILWAUKEE, WISCONSIN.

WORK-FEED-TRIPPING MEANS.

1,381,352.

Specification of Letters Patent. Patented June 14, 1921.

Application filed October 24, 1917. Serial No. 198,310.

To all whom it may concern:

Be it known that I, WILLIS S. SHERMAN, a citizen of the United States, and resident of Milwaukee, Milwaukee county, Wisconsin, have invented new and useful Improvements in Work-Fee-⁵ding Means, of which the following is a description, reference being had to the accompanying drawings, which are a part of this specification.

10 This invention has for its object to provide an end matcher or other machine having mechanism for feeding work with means tripped by the introduction of the work for starting the feeding mechanism in operation, 15 such tripping means being incapable of operation by the work unless the work is in proper position for engagement by the work feeding means.

In end matchers and the like for moving 20 long strips of flooring edgewise through a work guide and past cutters, it is necessary that the work be introduced in approximately its true position, that is at right angles to the line of feed. This is made 25 necessary by reason of the fact that the feed means engages the work at two distant points to feed it between pressure guides and maintain its true position, and an introduction of the work in other than its approximately 30 true position would prevent the engagement of the feeding means with the edge of the work at one of said points, with the result that a false operation would be performed.

35 In order to effect the operation of the work feeding means only when the work is introduced in position to be properly engaged by the feeding means at both points, the present invention provides triggers near 40 the points of engagement of the work feeding means with the work, which triggers are to be engaged and moved by the work on its introduction to the machine, and the operation of both of which is required to release 45 the clutch and start the feeding means in operation.

With the above and other objects in view, the invention consists in the work feed tripping means as herein claimed and all equivalents.

50 Referring to the accompanying drawings, in which like characters of reference indicate the same parts in the different views:

Figure 1 is a view of a work feed tripping means constructed in accordance with this 55 invention, the outline of parts of an end

matcher with which it is used being shown in dotted lines;

Fig. 2 is a plan view thereof;

Fig. 3 is a view of the trip mechanism at 60 right angles to the direction of the view of Fig. 1, with one of the hangers sectioned on the plane of line 3—3 of Fig. 1;

Fig. 4 is a similar view of the trigger mechanism with one end sectioned on the 65 plane of line 4—4 of Fig. 1; and

Fig. 5 is a sectional view of the clutch.

In these drawings 10 indicates in dotted lines the end matcher frame in which a cut-off saw 11 and matching cutters 12 are 70 mounted to operate on the strips of flooring as they are pulled through a work feeding passageway between a head block 13 and pressure bars 14 by means of hook bars 15 which are reciprocated by a swinging lever 75 16 mounted on a shaft 17, all of well known construction.

The oscillating feeding lever 16 is swung back and forth by suitable mechanism not shown but operated by a gear 18 on a clutch 80 sleeve or tubular driving shaft 19 carried by the driving shaft 20. The said clutch sleeve 19 is mounted in a bearing of the frame and has the driving shaft 20 journaled within it and a spring-pressed pin 21 slidably 85 mounted in the enlarged end of the clutch sleeve is adapted to engage any one of a number of clutch teeth 22 on a clutch head 23 which is keyed on the end of the driving shaft. Such clutch pin 21 may, however, be 90 held out of engagement with the teeth of the clutch head by engaging a cam segment 24 which normally lies within a groove 25 around the enlarged end of the clutch sleeve, the clutch pin extending across said groove 95 and having a notch registering therewith when it is withdrawn from engagement with the clutch head. This clutch construction is of a well known type and forms no part of the present invention except in combination, as will later appear.

100 The cam segment 24 is carried on one end of a pin releasing lever 26 which is fulcrumed on the frame, and a spring-actuated stop-arm 27, which is also fulcrumed on the frame, constitutes a spring dog for engaging the pin releasing lever by having a lug 28 adapted to engage a notch in the end of the pin releasing lever 26 to hold it normally within the groove 25 of the clutch so as to 110 keep the clutch pin 21 withdrawn. A stop 29 on the crank box 30, which is conven-

iently employed as the pivotal support for the stop arm 27 stands in the path of the clutch cam lever 26 to limit the downward movement thereof when it is released by the 5 lifting of the stop arm 27 by means which will be later described.

The stop arm 27 is limited in its movements by having a projection 31 playing between a pair of stop shoulders 32 on the 10 crank box 30. This projection 31 has an eye in its end through which passes a connecting rod 33 with its lower forked end pivotally mounted on one arm of a double crank 34 which is fixed on the shaft 17 of the swinging work feed lever 16. Pairs of 15 jam nuts 35 on the connecting rod 33 form adjustable spring seats for a compression spring 36 bearing on the upper face of the projection 31 of stop arm 27, and for a compression spring 37 bearing on the lower 20 face of said projection.

The other arm of double crank 34 is connected by a connecting rod 38 with the lower end of clutch cam lever 26, the said connecting rod sliding through the end of the clutch cam lever and having compression springs 39 and 40 seated on adjustable set nut seats 41 thereon and bearing on opposite sides of the clutch cam lever.

30 Hangers or bracket bearings 42, which may incidentally constitute stops for the hook bars 15 of the machine are suitably fastened to the frame so as to be immovable, and a trip lever shaft 43 is journaled in the bearing formed at the lower ends thereof. This trip lever shaft has a pair of trip levers or arms 44 formed on it or otherwise rigid therewith and these trip levers or arms 44 are normally engaged by hooks 45 pivotally 35 suspended from bolts 46 projecting inwardly from the hanger brackets 42. The engagement of the hooks 45 prevents the downward movement of the arms 44 and said arms have arc-shaped projections on their ends for permitting them to return into engagement with the hooks after they have been released thereby. The trip lever shaft 43 also has fixed on it at one end, a crank arm 47 which is connected by a connecting rod 48 with the 40 end of stop arm 27, this connection between the connecting rod 48 and the stop arm 27 being preferably made adjustable by the connecting rod fitting in an eccentric opening in a bushing 49 rotatable in a cylindrical 45 sleeve on the end of the stop arm and held in its adjustments by a set screw 50.

Each hook 45 has a connecting rod 51 connecting it with an adjusting collar 52 on a contact finger 53. These contact fingers 53 50 are loosely mounted on a shaft 54 which is suitably supported by having its ends fitting in the grooved guides formed by the head block 13 and through which the hook bars travel. The contact fingers are locked with 55 their lower ends as close as possible to the

line of travel of the hook bars and are rotatably adjustable within their adjusting collars 52 so that a line connecting them would be at right angles to the direction of the feed of the work through the machine. 70 The lower ends of the contact fingers project into the work feeding passageway to be engaged and swung when a strip of work is inserted in the work feeding passageway and is pressed in the direction of feed. 75

The arrangement of the compression springs is such that in the normal position of the parts, as shown in Fig. 1, spring 39 is under compression tending to throw the clutch cam lever 26 so as to move the cam segment 24 out of the clutch groove to permit the engagement of the clutch for starting the work feeding lever 16 in motion. This action, however, is prevented by the engagement of the lug 28 of the stop arm 85 with the notch of the clutch cam lever 26. Also spring 36 is under compression tending to swing the stop arm 27 upwardly out of its engagement with the clutch cam lever 26, but this action is prevented by the inability of the trip lever shaft 43 to turn, owing to the engagement of the hooks 45 with the levers 44 thereof. The proper introduction of the work, however, which causes both contact fingers to swing and pull 90 the hooks 45 out of engagement with the levers 44, removes this obstacle and the shaft 43 is turned and the stop arm 27 is raised by the pressure of the spring 36 on the projection 31. This lifting of the stop arm 100 removes the lug 28 from engagement with the clutch cam lever and the spring 39 throws the latter to remove the cam segment from the groove of the clutch, whereupon the clutch pin 21 engages one of the teeth of the 105 clutch head 23 for coupling the driven parts with the driving shaft for one cycle of operation of the work feeding means. The clutch cam lever 26 engages the stop 29 for limiting its movement in withdrawing the 110 cam segment from the clutch groove.

In performing its cycle of operation, the work feeding means changes the condition of the various springs so as to restore the parts to their normal positions. The shaft 115 17, which forms a part of said work feeding means, being rigidly connected with the work feeding lever 16, which operates the work feeding bars 15, serves to oscillate the double crank 34. In the first part of its 120 movement, to the left as shown in Fig. 1, it serves to compress spring 40 and by means thereof return the clutch cam lever 26 to the position in which its cam segment enters the clutch groove. At the same time spring 125 37 is compressed to return the stop arm 27 to its position for engaging and holding the clutch cam lever 26 in the position to which it is moved. This movement of stop arm 27 returns the trip lever shaft 43 to its normal 130

position and the work having passed the contact fingers the hooks 45 are free to re-engage the levers 44 and thus lock all parts in their normal positions during the return movement of the double crank 34, to the right as shown in Fig. 1. During this return movement of the double crank 34 the only change that takes place in the clutch-actuating mechanism is the removal of pressure from springs 40 and 37 and the compression of springs 39 and 36 to prepare them for the succeeding releasing operation.

It will be understood that inasmuch as the release of the clutch depends upon the movement of both contact fingers to withdraw both hooks 45, the proper positioning of the work in the work feeding passageway is assured. Should the work be introduced at an angle to its true position as shown at α in Fig. 2, so that its rear edge is not in position to be engaged by the hooks of both work feeding hook bars only one contact finger 53 would be swung and consequently only one hook 45 would be released from its engagement with the trip lever shaft and the other would remain to prevent the operation of the clutch. Should the work be deliberately pushed into the machine in this position, the clutch would not be operated until the second contact finger 53 is swung and at such time the rear edge of the work would be in position to be engaged by the hooks of both hook bars and the correction in the position of the work would be performed by the feeding mechanism and the coöperation of the pressure bars therewith in a manner forming no part of the present invention.

The work feed tripping means of this invention requiring the joint operation of two triggers spaced apart prevents the feeding mechanism being started in operation at a time when the descent of one hook bar would bring its hook down in advance of the rear edge of the work, thus preventing a proper engagement with the work and possibly resulting in an injury to the machine.

This application in part constitutes a division of my application Serial No. 844,936, for end matchers, filed June 13, 1914.

What I claim as new and desire to secure by Letters Patent is:

1. In a machine having a definite cycle of operation, a driving shaft therefor, driving means for said shaft, a pin clutch controlling the connection between the driving means and said shaft, a pin-releasing lever fitting in the groove of the clutch, a spring dog engaging the pin-releasing lever to hold it in the groove of the clutch, suitably operated means connected with the dog for releasing the dog from engagement with the pin-releasing lever, a rod connecting the pin-releasing lever with an operated part of the machine for receiving movement therefrom,

and springs on said rod bearing on opposite sides of the pin-releasing lever.

2. In a machine having a definite cycle of operation, a pin clutch establishing connection between the driving and driven parts thereof, a pin releasing means having a tendency to move away from the clutch, a dog for holding the pin releasing means in engagement with the clutch, and means operated by the movements of the machine for returning the pin releasing means to its engagement with the clutch.

3. In a machine having a definite cycle of operation, a pin clutch connecting together the driving parts and the driven parts thereof, a pin releasing member, having a tendency to move away from the clutch, a suitably released dog engaging the pin releasing member and holding it in engagement with the clutch, and means operated by the movements of the machine for returning the pin releasing member to its engagement with the clutch and for reengaging the dog therewith.

4. In a machine having a definite cycle of operation, a pin clutch for connecting the driving and driven parts thereof, a spring retracted pin releasing lever adapted to enter the groove of the clutch to disengage the clutch pin, a spring retracted dog for holding the pin releasing lever in the clutch groove, means for holding the dog in engagement with the pin releasing lever, and means set in motion by the cycle of operation of the machine for moving the pin releasing lever into the groove of the clutch and for moving the dog into engagement with the pin releasing lever.

5. In a machine having a definite cycle of operation, a pin clutch connecting the driving parts and the driven parts thereof, a pin releasing lever for the clutch, a dog for holding the pin releasing lever in its engagement with the clutch, means for releasing the dog, and means operated by the machine during its cycle of operation for moving the pin releasing means and the dog to their engaging positions and then subjecting them to spring action tending to move them from such positions.

6. In a machine having a definite cycle of operation, a pin clutch connecting the driving and driven parts thereof, a pin releasing means for the clutch, a releasable dog for holding the pin releasing means in engagement with the clutch, and means operating with the machine during its cycle of operation for first moving the pin releasing means into engagement with the clutch and then giving it a tendency to move away from the clutch.

7. In a machine having a definite cycle of operation, a pin clutch for connecting the driving parts with the driven parts thereof, a pin releasing member for the clutch, means

operated by the movements of the machine during its cycle of operation for returning the pin releasing means to the clutch and then giving it spring pressure away from the clutch, and a suitably releasable dog for engaging and holding the spring releasing member in engagement with the clutch against the action of such spring pressure.

8. In a machine having a definite cycle of 10 operation, a pin clutch for connecting the driving parts and the driven parts thereof, a pin releasing lever having a cam segment for engaging and releasing the pin of the clutch, a pivotally mounted stop arm engaging the pin releasing lever, and reciprocating rods passing through the pin engaging lever and the stop arm respectively and having springs with adjustable spring seats and bearing on opposite sides of the pin releasing lever and the stop arm, said rods having operative connection with the machine to be reciprocated thereby with each cycle of operation.

9. In a work feeding means having a definite cycle of operation, a clutch for connecting the driving parts with the driven parts thereof, a means for operating the clutch, and a pair of triggers for controlling the operating means and adapted to be engaged 25 and moved jointly by the work in order to operate the clutch to start the work feeding means.

10. In a work feeding means for wood working machinery, a pair of triggers positioned at definite points for engagement 35 with the work when the work is properly presented to the machine, and operating mechanism independently restrained by the said triggers and requiring the joint operation of the triggers for its release.

11. In a work feeding means for wood working machines, having work engaging means adapted to be operated at certain points, a pair of triggers in position to 45 be engaged by the work only when the work is in position to be engaged at such points, and operating means independently restrained by said triggers requiring the joint operation of the triggers for its release.

50 12. In a work feeding means for wood working machines, a pair of triggers positioned in the path of the work on being properly introduced, hooks connected with the triggers, a shaft having arms engaged by 55 the hooks, and a clutch controlling means connected with the shaft for starting the

machine in operation when the arms are released by the hooks.

13. In a clutch controlling means for the work feeding mechanism of wood working 60 machines, a pair of triggers in position to be engaged by the work on its proper introduction to the machine, hooks connected therewith, a shaft having arms engaged by the hooks, a dog connected with the shaft, 65 and clutch operated means having a tendency to move in one direction and engaged and held by the dog.

14. A clutch operating means for the work feeding mechanism of wood working 70 machines, comprising a pair of triggers in position to be engaged by the work when the work is properly presented to the machine, a pair of hooks connected with the triggers, a shaft having arms engaged by 75 the hooks, a crank arm on the shaft, a pivotally mounted dog, a connecting rod connecting the dog with the crank arm, a pin clutch for connecting the driving parts of the work feeding mechanism with the driven parts 80 thereof, and a pin releasing member having a tendency to move away from the clutch and held in engagement with the clutch by said dog.

15. A clutch operating means for the work 85 feeding mechanism of wood working machines, comprising a pair of contact fingers forming triggers in position to be engaged by the work when it is properly presented to the machine, arms adjustably mounted on 90 the triggers, connecting rods connected with said arms, hooks connected with the connecting rods, a shaft having arms engaged by the hooks, a crank arm on the shaft, a pivotally mounted stop arm, a connecting rod on the 95 crank arm having adjustable connection with the stop arm, a pin clutch for connecting the driving parts of the work feeding mechanism with the driven parts thereof, a pin releasing lever engaging the clutch pin, 100 a lug on the stop arm engaging the pin releasing lever, and reciprocating rods operated by the work feeding means and having spring engagement with the opposite sides of the pin releasing lever and the stop 105 arm respectively.

In testimony whereof, I affix my signature, in presence of two witnesses.

WILLIS S. SHERMAN.
